UNITED STATES PATENT OFFICE.

MORRIS ZUTMAN, OF CHICAGO, ILLINOIS.

LOCK GUARD.

1,413,883.

Specification of Letters Patent. Patented Apr. 25, 1922.

Application filed August 26, 1918. Serial No. 251,360.

To all whom it may concern:

Be it known that I, MORRIS ZUTMAN, a citizen of the United States, residing at Chicago, in the county of Cook and State of Illinois, have invented a certain new and useful Improvement in Lock Guards, of which the following is a full, clear, concise, and exact description, reference being had to the accompanying drawings, forming a part of this specification.

The invention relates to automatically operable latch or lock guards, and has as its object the production of a device of this character which may cooperate with and be actuated by a movable window or other element to prevent the operation of the latch, when said window or other element is moved to any of its intermediate positions.

The invention will be described in connection with a vehicle top having windows which may be shifted to produce an open or closed type, and which has a door whereby access may be had to the vehicle, the door being in the path of the movable window and having a latch or lock which is prevented from being operated to open the door when the window is in any of its intermediate positions, thereby preventing the breakage of the glass of the window or injury to the frame in which the glass is confined.

The invention has as its object the production of a device of this character which will produce these and other advantages in a simple and expeditious manner.

One embodiment of the invention is herein shown and described, in connection with the accompanying drawings, in which

Fig. 1 is a sectional view of a vehicle body showing the invention applied thereto;

Fig. 2 is a side elevation of a vehicle door showing in detail the mechanism employed, whereby the operation of the lock is prevented;

Fig. 3 is a vertical section illustrating the relative position of some of the parts when the movable window is brought into operative position with the mechanism shown in Fig. 2; and

Fig. 4 is a fragmental view similar to that shown in Fig. 2, illustrating a modified construction which may be resorted to.

In the accompanying drawings the device is shown as applied to a vehicle top 10 having the movable window 11 arranged in the rearmost portion of the top and which is movable along the guide 12 which extends

from one end to the other thereof. The top illustrated is provided with the doors 13 and 14, each of which is respectively provided with the windows 15 and 16, which are held against sidewise movement relatively to said doors and are arranged in a different plane than that in which the window 11 moves. Each of these doors carries a section of the guide 12 provided to form a guide for the movable window 11 and are further respectively provided with the mechanisms generally designated 17 and 18, which are in the path of movement of the movable window such as 11 and are operable by said movable window to engage and prevent the operation of the latches of the respective doors 13 and 14 thereby eliminating the possibility of said doors 13 and 14 being opened either from within or without, when the movable window 11 is caused to assume a position intermediate its normal position in rear of the top and the door, such as 13, or when arranged between this door and the door 14. The mechanism generally designated 17 is composed of the pivoted members 20 and 21, which are secured to the plate 22 which in turn is attached to the door 13. These members 20 and 21 are arranged in the path of the movable window 11 and are arranged at one side of the windows 15 and 16 of the doors 13 and 14. These members 20 and 21 are respectively pivotally connected to the plate 22 at 23 and 24, and have their ends pivotally connected together at 25. A pin 26 is provided to limit the movement of said members 20 and 21 in one direction. This plate 22 and the members which it carries is arranged upon the door so that the ends of the members 20 and 21 project into the path of the movable window. These ends are bent upwardly as shown at 28 and are provided with the beveled edges 27 and 29 so that each of these members may readily be depressed when the movable window engages them during its movement in either direction. One of the members as 20 is provided with the downwardly projecting rod 30, which is pivoted thereto at 31. This rod is provided for the purpose of engaging the bolt 32 of the lock 33 to prevent the manipulation of the lever 34, and consequently the bolt 32, when the movable window 11 is in an intermediate position. To accomplish this the bolt is recessed 35 as at 35 to receive the rod when the same is depressed by the engagement of either of the

members 20 or 21 with the movable window 11. A coiled spring 36 is provided which is arranged upon the rod 30 and reacts between the pivoted member 20 and the casing 5 of the lock 33. This spring permits the levers 20 and 21 to yield when engaged by the movable window 11 and restores said members to their normal position when the movable window passes beyond said levers 10 20 and 21. It will be understood that the pin 26 limits the upward movement of the free end of the levers 20 and 21. The levers 20 and 21 are encased in the housing 37 which is fastened to the side of the door and 15 extends over the uppermost edge thereof and is provided with the rib 38 which forms a part of the guide upon which the window 11 travels when moved. The particular frame in which the window is mounted is formed 20 of a suitable strip of metal which is provided with the downwardly facing grooved portion 39, the upwardly facing grooved portion 40, and the laterally extending flanged portion 41.

25 The groove 39 rides upon the rib 38 of the housing 37 when the window is moved across the door. The groove 40 receives the glass of the movable window and the laterally extending flange 41 is provided to engage and depress the ends of the levers 20 and 21 to cause the rod 30 to be moved into engagement with the bolt 32 which prevents its operation. The housing 37 is provided with the slot 42 in which the handle of the 30 lever 34 operates when moved to operate the bolt 32.

The particular lever mechanism employed in connection with the door 14 may only utilize one lever such as 45, which is pivotally held at one end and has its opposite end provided with the curved portion 46, the rod 47 and the spring 48, which operates in the same manner as does the mechanism employed in connection with the door 13, when 45 this structure is engaged by the movable window 11.

In Fig. 4 is shown a modified construction differing from that shown in Fig. 2, in that a means is provided which instead of engaging the bolt of the lock engages the lever which operates the bolt. In this instance one of the levers 49 is provided with a plate or other obstruction which is positioned in the path of movement of the lever 50 of 50 the lock mechanism when the movable window 55 causes its operation, thus preventing the operation of the bolt which the lever controls.

From the foregoing description of the mechanism employed in connection with the door 13 it can readily be seen that when the movable window 11 is actuated and brought into contact with either of the levers 20 or 21 of this mechanism, the bolt or lock will be engaged and its operation 60 to open the door prevented, thus eliminating

the possibility of breaking the glass of the movable window 11 when same is in an intermediate position. It is further evident that an extremely simple arrangement for accomplishing the end sought is provided, 70 which is simple and effective in operation and construction. Whereas the structure shown is described in connection with a window which is movable to and from the rear of the vehicle. It is understood that the invention is not limited to the particular arrangement, the scope thereof being defined by the appended claims forming a part hereof.

Having thus described one embodiment of 80 the invention, what I claim and desire to cover by Letters Patent is:

1. A vehicle top having a swinging door and a movable window, means for releasably locking the door and independently operable means for engaging and releasing the locking means to prevent and permit the actuation thereof, said means being controlled by the movable window.

2. In a device of the class described, the 90 combination of a door and a movable window, a lock for the door, said lock being operable to automatically lock the door against opening when the door is moved to closed position and being manually operable to effect an opening of the door and means controlled by the movable window for engaging and releasing the lock to prevent and permit the operation of said lock.

3. In a vehicle top the combination of a 100 door and a movable window, means for locking the door and independently operable means for engaging the locking means to prevent its actuation and the opening of the door, said last mentioned means being operable by the movable window.

4. A vehicle top having a door and a window, said window being arranged at one end of the top and being movable toward the opposite end of the top and beyond the door, 110 a lock provided in said door, said lock including a spring actuated bolt which normally projects beyond the door, means for engaging the lock to prevent its operation when the door is closed, said means being carried by the door, and operable by the window, said means having a portion arranged in the path of the movable window, and being operable to release the lock when the window is moved beyond the door.

5. A vehicle top having a door and a window, said window normally occupying a position at one end of the top, a lock provided in said door, said lock having a bolt which normally projects beyond the door, and means for engaging the lock, said means being carried by the door and including a lever one end of which extends beyond the door and is engageable by the window when moved, and constructed to engage the lock 125 130

to prevent the operation thereof when the window is moved towards the door.

6. A vehicle top having a door and a window, said window being normally arranged at one end of the top and being movable towards the opposite end thereof, the door having a lock said door being arranged in the path of the movable window and having means for engaging and preventing the operation of the lock, said means including a pair of levers the ends of which are secured together, the opposite ends of the levers extending into the path of the movable window and operable thereby when the window is moved, and means secured to one of said levers constructed to engage the lock to prevent its operation when the window is in engagement with one of said levers.

7. A vehicle top having a door and a movable window, a lock for the door, said lock being automatically operable to permit the door to assume a closed position and to hold said door in said last named position, means for engaging the lock when the window is moved towards the door, said means including the movable window, and means whereby the lock is released when the movable window is moved beyond the door.

8. In a vehicle top the combination of a door and a movable window, a lock for the door, means for engaging the lock and releasing the same, and means for actuating said means, said last mentioned means including a pair of levers having their ends pivotally connected together, the opposite ends of said levers being arranged in the path of the movable window.

9. In a vehicle top the combination of a door and a movable window, a lock for the door, independently operable means for en-

gaging the lock to prevent its operation and releasing the same to permit its operation, and means for actuating said means, said last mentioned means including a yieldable lever having an end arranged adjacent an edge of the door and in the path of the movable window.

10. In a vehicle top the combination of a door and a movable window, a lock for the door vertically movable, means for engaging and releasing the lock, and means for actuating said last mentioned means, said last mentioned means having means arranged adjacent the edges of the door, and in the path of the movable window.

11. In a vehicle top the combination of a door and a movable window, a lock for the door, means for engaging the lock and releasing the same, and means for actuating said last mentioned means, said last mentioned means including a pair of levers each having an end which is arranged adjacent the edges of the door and in the path of the movable window.

12. In a vehicle top the combination of a door and a movable window, a lock for the door, said lock including a reciprocal bolt which normally extends beyond the door and is operable to recede and again extend during the closing of the door, means for engaging the bolt to prevent its operation, said means being constructed to release the bolt to permit it to be operated to open and close the door and hold said door in said last named relation, said means being operable by the movable window.

In witness whereof, I hereunto subscribe my name this 19th day of July A. D., 1918.

MORRIS ZUTMAN.
